UNITED STATES PATENT OFFICE.

GEORGE S. GATCHELL, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

PRESSER FOOT FOR SEWING MACHINES.

Application filed May 26, 1922. Serial No. 563,864.

To all whom it may concern:

Be it known that I, GEORGE S. GATCHELL, a citizen of the United States, residing at Roselle Park, in the county of Union and State of New Jersey, have invented certain new and useful Improvements in Presser Foot for Sewing Machines, of which the following is a specification, reference being had therein to the accompanying drawings.

10 This invention relates to presser-feet for sewing machines and has for an object to provide a presser-foot under which work with heavy cross-seams may be fed by the usual four-motion feed-dog with substantially the same degree of certainty, uniformity and facility as work of constant thickness.

Another object of the invention is to provide the presser-foot with improved and simplified means to prevent the skipping of stitches when the needle or needles of the machine pass from a heavy cross-seam or thick portion of the work to a thinner portion.

25 According to the present improvement, the presser-foot comprises a shank and pivotally mounted sole-piece with which is combined a stripper-foot pivotally mounted to rock independently of the sole-piece. 30 The stripper-foot has at its free end a downwardly directed projection which rides upon the surface of work of varying thickness, closely adjacent the needle-path, regardless of the position or degree of elevation of the sole-piece.

35 The stripper-foot is recessed at its under side between its pivot and the free end to afford clearance permitting the downwardly extending projection to drop abruptly from a heavy cross-seam to a thinner portion of the work, immediately upon passage of the cross-seam to the rear of such projection, and hold the thin portion of the work upon the throat-plate and prevent its rising with the needle while the sole-piece is held at a higher level by the cross-seam.

In the accompanying drawings, Fig. 1 is a fragmentary elevation of a sewing machine embodying the invention; showing the 40 presser-foot in side elevation and a heavy

cross-seam approaching the presser-foot. Fig. 2 is a similar view showing the cross-seam under the main part or sole-piece of the presser-foot. Fig. 3 is a rear elevation, Fig. 4 a front elevation, and Fig. 5 a top plan view of the presser-foot shown in Figs. 1 and 2. Fig. 6 is a disassembled perspective view of the presser-foot. Fig. 7 is a view similar to Fig. 1 of a modified form of the presser-foot embodying the invention. Fig. 8 is a view of the modified presser-foot resting upon a cross-seam and Fig. 9 is a top plan view of the presser-foot shown in Figs. 7 and 8.

In the preferred embodiment of the invention, as illustrated in Figs. 1 to 6, inclusive, 1 represents the presser-foot shank which is adapted to be attached as usual to the spring-pressed presser-bar 2 of a sewing machine of ordinary construction including the reciprocating needle-bar 3 carrying one or more needles 4 which cooperate with suitable loop-taking means (not shown) below the throat-plate 5 to form stitches. The throat-plate 5 is slotted as usual at 6 for passage of the four-motion feed-dog 7.

Pivoted to the shank 1 by means of the pin 8 is the sole-piece 9 having one or more apertures 10 for the needle or needles 4. The front end of the sole-piece 9 is slotted at 11 to form toes 12 which are turned upwardly to facilitate passage of the work thereunder. Pivoted to the shank 1, preferably by means of the pin 8, is the stripper-foot which is in the form of a pair of spaced parallel arms 13 joined at their front ends by a cross-bar 14 from the center of which a short toe 15 projects rearwardly and downwardly and has a rounded extremity which is received in the slot 11 in the sole-piece 9. The arms 13 of the stripper lie along the opposite sides of the sole-piece 9 and are formed at their forward ends with downwardly extended projections 16 which are rounded similarly to the extremity of the central member or toe 15. The arms 13 of the stripper are recessed at their under sides at 17, between the projections 16 and the pivot 8 to permit the projections to drop from a thick to a thin portion of the work,

immediately upon passage of the thick portion to the rear of said projections.

The arms 13 are extended rearwardly of the pivot 8 and are formed with recesses 18 for the upper ends of the springs 19 the lower ends of which are received in the recesses 20 in the heel portion of the sole-piece 9. The stripper preferably is extended somewhat in advance of the sole-piece 9 to engage a cross-seam before it reaches the sole-piece. The cross-bar 14 is arranged so that its lower rearward edge 14', Fig. 1, will engage and lift the toes 12 when a cross-seam 21 passes under the projections 16. When the cross-seam 21 passes the projections 16, the latter drop quickly to the position shown in Fig. 2 and hold the thin portion 22 of the work upon the throat-plate 5, preventing such portion 22 from rising with the needle or needles and thus insuring the formation of the needle-loops for seizure by the loop-taking means.

Clamped to the presser-bar bushing 2^a is a collar 2^b carrying a downwardly extending vertical bar 2^c the lower end of which terminates directly above the rear end portion of one of the arms 13 of the stripper. When the presser-foot is lifted, as by means of the usual presser-foot lifting lever 2^d, the bar 2^c serves as an abutment for the stripper-foot and holds the rearward end of such foot depressed and the front end elevated, as shown in Fig. 3, to facilitate insertion and removal of the work.

According to the modified form of the invention illustrated in Figs. 7, 8 and 9, the shank 23 has pivoted thereto at 24 the sole-piece 25 which is formed with the upturned forward extremity or toe 26 and needle-apertures 27 between which the sole-piece is longitudinally slotted at 29 for reception of the stripper-arm 30 which is disposed centrally of the presser-foot and is pivoted on the pin 24. A spring 31 disposed in a recess in the shank 23 presses outwardly upon an arm 32 rigid with the stripper-arm 30 and yieldingly forces the latter into engagement with the work. The arm 30 is formed at its free end with a downwardly extending rounded projection 33 similar in function to the projections 16 of the stripper-foot illustrated in Figs. 1 to 6 inclusive. The arm 30 is also recessed at 34 between the projection 33 and the pivot 24 to enable the projection 33 to drop quickly from a heavy cross-seam 21 to thinner work 22, as illustrated in Fig. 8. The projection 33 engages the work between the needles 4 and acts as a stripper while sole-piece 25 is held in an elevated position by the cross-seam 21.

The particular presser-feet disclosed are adapted, more particularly, for lap-seam felling in a two-needle double-chain-stitch machine and, to this end, the stripper shown in Figs. 1 to 6, inclusive, is formed with

guiding flanges 35 while the sole-piece 25 of Figs. 7, 8 and 9 is formed with similar guiding flanges 36.

The invention is doubtless susceptible of embodiment, by those skilled in the art, in forms other than those specifically shown and described. For an understanding of the scope of the invention reference should therefore be had to the appended claims.

Having thus set forth the nature of the invention, what I claim herein is:—

1. A presser-foot for sewing machines having, in combination, a shank, a main sole-piece directly pivoted to said shank and having a limited tilting movement, a stripper-foot pivoted to said shank and having at its forward end a downwardly extending projection, said stripper-foot being recessed intermediate its pivot and said projection to permit the latter to engage a thin portion of the work while said sole-piece rests upon a thicker portion of work.

2. A presser-foot for sewing machines comprising a shank, a flat sole-piece and a stripper-foot pivoted independently of one another coaxially to said shank, said stripper-foot having at its forward end a downwardly extending projection and being recessed at its under side intermediate said projection and its point of pivotal connection to said shank.

3. A presser-foot for sewing machines comprising a shank, a sole-piece and a stripper-foot pivoted independently of one another to said shank, said stripper-foot being extended in advance of said sole-piece and having a downwardly extending projection and a recess in rear of said projection, said stripper-foot also having means adapted to lift the front end of said sole-piece as work of increased thickness passes under said stripper-foot.

4. In a sewing machine, a presser-foot, means for lifting the presser-foot, a spring-pressed stripper-foot pivotally mounted on said presser-foot, and an abutment for turning said stripper-foot about its pivot against the action of its spring when the presser-foot is lifted.

5. A presser-foot for sewing machines comprising a shank, a sole-piece and a stripper-foot pivoted independently of one another to said shank, and a spring mounted independently of said shank to react in opposite directions against said sole-piece and stripper-foot.

6. A presser-foot for sewing machines comprising a shank, a sole-piece and a stripper-foot pivoted co-axially to said shank, said sole-piece being formed with a needle clearance aperture and said stripper-foot having on its underside a downward projection and a recess in rear of said projection.

7. A presser-foot for sewing machines

comprising a shank, a sole-piece directly pivoted to said shank and having a limited tilting movement, and a stripper-foot pivoted to said shank and having at its front end a downward projection adapted to extend below the work engaging surface of said sole-piece in passing over a cross-seam;

the stripper-foot being with the exception of said projection disposed wholly above said work-engaging surface so as not to press up-¹⁰ on the work in rear of said projection.

In testimony whereof, I have signed my name to this specification.

GEORGE S. GATCHELL.
